UNITED STATES PATENT OFFICE.

GEORGE L. DILLARD, OF MOGOLLON, NEW MEXICO, ASSIGNOR TO THE CAPSEAL COMPANY, OF EL PASO, TEXAS, A CORPORATION OF TEXAS.

PROTECTOR FOR DETONATOR-CAPS.

1,242,781.

Specification of Letters Patent.

Patented Oct. 9, 1917.

Application filed November 15, 1916. Serial No. 131,432.

To all whom it may concern:

Be it known that I, GEORGE L. DILLARD, a citizen of the United States, and a resident of Mogollon, in the county of Socorro and State of New Mexico, have invented a certain new and useful Improvement in Protectors for Detonator-Caps, of which the following is a specification.

My present invention relates generally to blasting devices, and more particularly to the detonating caps to which the fuses are attached for blasting purposes, my object being to provide a protecting device therefor in order to seal the inner end of the cap 15 into which the adjacent end of the fuse is projected in use.

A further object of my invention is to provide a protecting device for the above purpose which will be simple in construction, which will be inexpensive for the purpose, and which may be readily secured in connection with the inner end of the cap and the portion of the fuse adjacent thereto, by the tools ordinarily used for securing the 25 cap in connection with the fuse.

With these objects in mind, my invention resides in the protecting device to be now described in connection with the accompanying drawings, forming a part of 30 this specification, and wherein—

Figure 1 is a detail perspective view of a detonator fuse and cap illustrating the practical application of my invention;

Fig. 2 is a cross section therethrough 35 taken substantially on line 2—2 of Fig. 1;

Fig. 3 is a detail longitudinal section on an enlarged scale, taken substantially on line 3—3 of Fig. 2;

Fig. 4 is a sectional view through the cap 40 and fuse, prior to the application of my invention thereto, and

Fig. 5 is a longitudinal section through my improved protecting device removed.

Referring now to these figures, I have 45 shown a detonator cap at 10 in Figs. 1 to 4 inclusive, which is as usual in the form of an elongated cylinder, closed at its outer end 11, and open at its inner end for the reception of the adjacent end of the fuse 12, the bore 50 of the cap being slightly larger than the diameter of the fuse for this purpose.

It is well known, however, that, in utilizing a detonator of the character shown under water or in damp places, there are many

instances of failure to explode due to the 55 encroachment of moisture within the cap, giving rise to more or less considerable loss in supplies as well as creating considerable danger.

In order to obviate these disadvantages, I 60 provide a protecting device consisting of a cylindrical holder 13, open at both ends and with its ends crimped as at 14 for a purpose to be presently described, the diameter of the cylindrical holder even at its 65 crimped ends being slightly greater than the outside diameter of the cap 10, in order that it may be readily slipped over the cap to the inner end thereof for the purpose of lapsing the said inner end of the cap and 70 thus surrounding a portion of both the cap and the fuse 12, as clearly seen by reference to Figs. 3 and 4, in the latter figure of which the position of the holder 13 is indicated in dotted lines. 75

This holder 13, of the shape described, is formed of a thin stiff material, which, though deformable, is capable of retaining a given shape, being deformable by means of the ordinary cap crimper, along a longitudinal line as clearly seen by reference to Figs. 1 and 2, whereby to more snugly embrace the portion of the cap and fuse surrounded thereby, the holder 13 having an inner film or lining 15 of a plaster water excluding material, such as paraffin which, when the holder is crimped, as just above described, is forced into the crevices between the fuse 12 and the adjacent end of the cap 10, so as to effectively seal the latter against 85 the ingress of moisture likely to otherwise bring about a misfire, as above stated. 80

Thus, the crimped ends 14 of the cylindrical holder 13 normally serve to retain the film or lining 15 in place and as guides to the 90 thickness of the film or lining, when originally placed within the holder. 95

It is obvious that my improved protector will serve to effectively seal the inner end of the cap and prevent entrance of moisture 100 thereto, without adding materially to the cost of the supplies, and that it will, in addition, more than save its cost in the reduction of misfire from dampness, in its use.

I claim:—

1. A protector for detonator caps, consisting of a deformable cylindrical holder, open at both ends thereof, and having an inner

105

- film or lining of a plastic water-excluding material normally carried by and forming a part thereof, for the purpose described.
2. A protector for detonator caps, consisting of a deformable cylindrical holder open at both ends thereof, and having an inner film or lining of a plastic water-excluding material, and also having crimped ends to normally retain the inner film or lining in place and act as a gage to the depth thereof, for the purpose described.
3. The combination with a detonator fuse and cap, of a protector including a cylindrical holder crimped along a longitudinal
- line around the inner end of the cap and a 15 portion of the fuse adjacent thereto, to snugly embrace the same, said holder having an inner film or lining of plastic water-excluding material whereby to seal the inner end of the cap around the fuse. 20
4. A protector for detonator caps, consisting of a deformable cylindrical holder, open at both ends, and provided with an inner film or lining of a plastic water-excluding material, and with means for holding said 25 film or lining therein as a part thereof.

GEORGE L. DILLARD.
